UNITED STATES PATENT OFFICE.

JOHN FAUNTLEROY MCGILL, OF VALLEJO, CALIFORNIA.

SHELL.

1,191,713.

Specification of Letters Patent. Patented July 18, 1916.

Application filed December 17, 1915. Serial No. 67,325.

To all whom it may concern:

Be it known that I, JOHN F. MCGILL, a citizen of the United States, residing at Vallejo, in the county of Solano and State of California, have invented new and useful Improvements in Shells, of which the following is a specification.

This invention is an improved shell of the delayed explosion type.

10 One of the objects of the invention is to provide a shell capable of effecting the destruction, or the substantial disabling of air craft, wireless installations ashore and afloat, wire entanglements, telegraph and tele-
15 phone lines, signal halyards and the like.

A further object of the invention is to provide a shell capable of carrying a large number of chain shot, or other similar projectiles.

20 A further object is to so arrange the chain shot or the like that upon bursting of the shell, said shot are accurately distributed over a wide area so as to have a maximum destructive effect.

25 A further object is to provide a shell of the character above referred to by means of which the various shot may be directed to predetermined known parts of the beaten zone, by providing means whereby the re-
30 spective shot may be delivered at different velocities.

35 A further object is to provide a shell in which the shot are so arranged that upon expansion of the shell, the centrifugal force developed by rotation of the shell will project the shot on a tangent from the shell body.

40 A further object is to provide means whereby the shot may be caused to travel on different predetermined tangents.

The invention will be hereinafter fully set forth and particularly pointed out in the claims.

In the accompanying drawings:—Figure 45 1 is a side elevation, parts being broken away. Fig. 2 is a longitudinal sectional view. Fig. 3 is a transverse sectional view on line 3—3 Fig. 2. Fig. 4 is a transverse sectional view on line 4—4 Fig. 2. Fig. 5 is a transverse sectional view on the line 5—5, Fig. 2. Fig. 6 is a detail view illustrating the supporting disk. Fig. 7 is a detail view of one of the supporting trays. Fig. 8 is a

detail view of one of the spacers. Fig. 9 is a detail view of one of the shots. Fig. 10 is a detail view illustrating one of the auxiliary shot retaining devices. Fig. 11 is a perspective view illustrating the loading device. Fig. 12 is a diagrammatic view illustrating the action of the shell when exploded. Fig. 13 is a detail perspective view, partly in section, illustrating the gas channels. Fig. 14 is a detail view of the base disk.

Referring to the drawing, 15 designates the base, 16 the nose, and 17 the shell body, all of which may be of any well known construction, the nose being provided with the usual fuse or exploding element 18. Resting upon the base 15, is a locking ring formed of sections 20, each section being provided with a longitudinal rib 21, shaped to enter a longitudinal groove 22, in the shell body, to prevent rotation of the ring. The sections 20 are provided with exterior longitudinal recesses 23, which register with corresponding recesses 24, formed in the inner face of the shell body, said recesses co-operating to form gas channels which coincide with cut away portions 25, between the lugs 19 formed on the lower ends of the said sections 20. The base 15 is provided with a central, circular table or raised portion 26, having a groove 27, extending transversely thereacross. The inner faces of the sections 20 are provided with longitudinal grooves 28, eight of such grooves being illustrated in each of said sections. The number of grooves 28 may be varied without departing from the spirit of the invention, the number of such grooves shown in the drawing being arbitrarily selected for illustrative purposes only. The explosive charge 29 is carried in the nose of the shell in the usual and well known manner, and a tube 18a leads from the fuse well into the bursting charge, so as to insure of an ignition of the charge near the gas channels, and to avoid choking said channels with unburnt powder grains.

The space within the locking ring is divided into a plurality of horizontal spaces, each space being subdivided to form a plurality of chambers 30, any number of which may be employed, each space being illustrated in the drawing as divided into four chambers, which chambers will be herein-

after referred to as shot chambers. Said chambers are formed by means of a supporting disk 34 provided with radiating arms, and a sectional structure resting upon 5 a metal base disk 31, having a down turned projection or abutment 32, and an upstanding abutment 33, said supporting disk resting upon the circular table 26 so as to cover and close the groove 27. Resting upon the 10 base disk 31 is a spacer 35, preferably of approximate cross shape, the arms of which are in engagement with the grooves 28, it being understood that the said arms are adapted to engage any of said grooves, 15 whereby the radial position of said arms may be selectively varied, and rotation of the spacer prevented. The central body of said spacer is provided with vent openings 35^a. Resting upon the spacer 35 is a tray 20 36, provided with a downwardly extended abutment 37, arranged to engage any one of the arms of the spacer 35 beneath it. The tray 36 is also provided with an upstanding abutment 38. Resting upon the 25 first tray 36, is a second spacer 35, rotation of which is prevented by the grooves 28, an upstanding abutment 38 also engaging one of the arms of said spacer, the abutments 37 and 38 co-operating with the arms of the 30 spacers to prevent rotation of the trays. Superimposed upon the last mentioned spacer are the desired number of trays 36 and spacers 35, four of each being illustrated in the drawing, thereby providing sixteen 35 shot chambers 30. The shot comprise slugs 39 of any suitable or preferred shape, arranged in pairs connected by chains 40, or other suitable flexible connection capable of 40 withstanding the shocks to be imposed upon them in being projected from the shell, and in striking the target. Preferably the slugs are of such shape that they will conform to the contour of the shot chambers, and they are retained in position by means of 45 tabs or ears 41, formed integral with the trays 36, said tabs or ears being bent over during the loading operation to retain the shot in position.

In order to effect the convenient loading 50 of the shell, a special loading device has been designed, as illustrated in Fig. 11, but it will be understood that the present invention is not limited to any particular form of loading device or method of loading. The 55 loading device illustrated comprises a rod 42, provided with threaded portions 43 at each end, one threaded end being engaged with a suitably threaded opening in the supporting disk 34, and a corresponding opening in a disk 44^a. Attached to a tubular stem 45, is a disk 44, provided with a threaded opening to engage the other threaded end of the rod 42, said rod being inclosed by the tubular stem 45. An intermediate disk 44^a 60 is preferably clamped between the end of

stem 45 and the topmost tray 36. It will be noted that the disks 44 and 44^a are somewhat larger in diameter than the trays 36.

In loading the shell by means of the above described loading device, the shell body 17 is first engaged with the base 15, and the sections 20 of the locking ring are then placed in position. The lower end of the rod 42 is then engaged with the supporting disk 34 and then with disk 44^a, which latter disk 7 may rest upon a suitable table or other support, to maintain the rod 42 in an upright position. The base disk 31 is then placed in position upon the supporting disk, and then rotated until the abutment 32 engages an 8 arm of the supporting disk. A spacer 35 is then placed in position and rotated on the rod 42 until one of the arms thereof engages the abutment 38 of the supporting disk. Upon the spacer 35 is placed a tray 8^a 36, which in turn is rotated until its depending abutment engages one of the arms of the spacer beneath it. In like manner the desired number of spacers 35 and trays 36 may be alternately placed in position. 9^a After the last or top tray has been placed in position the disk 44^a is placed in position and the tubular stem 45 is placed over the rod 42, and the threaded ends of said rod are engaged with the disks 9^a 44, 44^a thereby clamping the trays and spacers in position, between the disks 44^a and 44^a, so that the assembled elements may be handled as a single unit. The said unit is turned over on its side, so as to be supported on the edges of the disks 44 and 44^a, and then the shot chambers 30 are loaded. The bottom series A may be loaded by first placing the chain in one of the compartments and placing the slugs 39 on top, said 10 slugs being shaped to conform to the periphery of the loading trays 36, after which the tab or ear 41 opposite said slugs is turned down, to retain them in position. All of the first series A of chambers are loaded in 11 a similar manner. The second series of shot chambers B may be loaded in a similar manner. The third series of chambers C are loaded by first placing the slugs in position with the chains on the outside, and the 11^a fourth series D are preferably located by placing part of the chain inside and part of the chain outside. In loading in the manner described for series C and D, auxiliary retaining devices 41^a may be employed. It 12 will be understood that the slugs and chains may be arranged in the respective chambers in any suitable manner, the above described arrangement being merely one of many that may be employed. After the shot chambers have been loaded the cradle disk 44^a is removed, and the assembled spacers and trays are inserted within the locking ring, the ends of the spacers engaging the grooves 28 to prevent the parts from rotating. 13

When the loaded trays rest upon the circular table 26, the rod 42 is unscrewed from disk 34, and said rod and the disks 44 and 44^x, and the tubular stem 45 are withdrawn, 5 the spacers and trays being thus left free to fly upon bursting of the shell. The nose of the shell may then be secured in position.

In Fig. 12 is diagrammatically illustrated the effect of the explosion of a shell loaded 10 in the manner above described and containing sixteen shot chambers comprising four chambers arranged in four sets. The bursting charge contained in the nose, when ignited by the fuse, will force the gas generated, 15 down through the gas channels formed by the recesses 23 and 24, on the outside of the locking ring, through the spaces 25, and then upwardly through the holes or openings 46 formed in the trays 36, and 20 through the vent openings in the spacers 35. The nose, the outside of the shell and the locking ring are released upon explosion, and are followed by the chain shot, the trays and spacers being scattered and checked by 25 wind pressure upon exposure. The shell is so constructed as to prevent the crushing or tangling of the chain and slugs. It will be noted that the shot chambers of series B and D are in alinement with each other, the 30 chambers of series A being at an intermediate angle to those of B and D, and the series C being at an angle intermediate A and B. It will be evident that this arrangement may be varied at will by varying the number 35 of grooves 28, and the corresponding positions of the spacers. In the arrangement illustrated, the shot of series A will be discharged on tangents at approximately right angles to each other and at the same velocity, 40 and the shot of series B correspondingly projected on tangents about midway between those of series A and about the same velocity. The shot from series C is delivered on a tangent between those of series 45 A and B, but at a much less velocity. The shot of series D are discharged on the same tangents as series B but at less velocity, all of which will be readily understood from Fig. 10. By placing the 50 slugs on a different radius, they are caused to travel on different tangents, and by placing the slugs at different distances from the center the velocity of delivery may be increased or decreased. It therefore becomes 55 possible to so arrange the shot of the different series as to direct them to certain known parts of the beaten zone (shot and fragment group of the shell). For instance, the shot of series A and B will throw with the same 60 speed, whereas series C and D will deliver with less velocity, and thus fill in dead spaces near the continuation of the trajectory of the shell. The velocity of delivery will be accelerated by such gas as has been forced 65 up inside of the locking ring, and by the par-

tial vacuum caused by the outward rush of the gases when the shell is ruptured outside of the locking ring.

In practice the bursting charge carried in the nose of the shell is slow burning and 70 comparatively very small. Its action is rather of a lifting nature and entirely different from the fast burning types. The nose and base are made comparatively heavy to balance the projectile and improve its 75 ballistic qualities, the object being to make the center of form and the center of gravity of the whole shell coincide.

Having thus explained the nature of my invention and described an operative manner of constructing and using the same, although without attempting to set forth all of the forms in which it may be made, or all of the forms of its use, what I claim is:—

1. An improvement in shells comprising a 85 shell body, means for dividing the interior of the shell body into radial shot chambers adapted to effect a tangential discharge of the shot, and means coöperating with said dividing means to selectively vary the tangents on which the shot may be discharged. 90

2. An improvement in shells comprising a shell body, means for dividing the interior of the shell body into a plurality of superposed series of radial shot chambers adapted 95 to effect a tangential discharge of the shot, and means coöperating with said dividing means to selectively vary the tangents on which the shot may be discharged.

3. An improvement in shells, comprising 100 a shell body, spacer members located within said body and having radiating arms dividing the interior of the shell into radial shot chambers adapted to effect a tangential discharge of the shot, and means coöperating 105 with said dividing means to selectively vary the tangents on which the shot may be discharged.

4. An improvement in shells comprising a 110 shell body, a locking ring inclosed therein, means coöperating with the locking ring for dividing the interior of the shell body into radial shot chambers adapted to effect a tangential discharge of the shot, and means coöperating with said dividing means to 115 selectively vary the tangents on which the shot may be discharged.

5. An improvement in shells comprising a shell body, a locking ring formed of a plurality of sections inclosed within said shell, 120 means coöperating with the locking ring for dividing the interior of the shell body into radial shot chambers adapted to effect a tangential discharge of the shot, and means coöperating with said dividing means to selectively vary the tangents on which the shot may be discharged. 125

6. An improvement in shells comprising a shell body, spacer members located within said body and having radiating arms divid- 130

- ing the interior of the shell into radial shot chambers adapted to effect tangential discharge of the shot, and means engaging said arms to prevent rotation of the spacer members. 5
7. An improvement in shells comprising a shell body, a locking ring inclosed therein, means for preventing rotation of said ring, and means selectively engaging said locking ring to divide the shell into radial shot chambers adapted to effect tangential discharge of the shot. 10
8. An improvement in shells comprising a shell body, a locking ring inclosed therein, means for preventing rotation of said ring, and spacer members having radiating arms to selectively engage the locking ring to form radial shot chambers adapted to effect tangential discharge of the shot. 15
9. An improvement in shells comprising a shell body, a plurality of superposed alternately arranged trays and spacers within said body dividing the same into radial shot chambers adapted to effect a tangential discharge of the shot, and means for preventing relative rotation of said shell body and said spacers. 20
10. An improvement in shells comprising a shell body, a plurality of superposed alternately arranged trays and spacers within said body dividing the same into radial shot chambers adapted to effect a tangential discharge of the shot, and means coöperating with said spacers to effect a selective variation of the tangents on which the shot may be discharged. 25
11. An improvement in shells comprising a shell body, a plurality of superposed alternately arranged trays and spacers within said body dividing the same into radial shot chambers adapted to effect a tangential discharge of the shot, and means for preventing relative rotation of said trays and said spacers. 30
12. An improvement in shells comprising a shell body, a plurality of superposed alternately arranged trays and spacers within said body dividing the same into radial shot chambers adapted to effect a tangential discharge of the shot, and means for preventing relative rotation of said trays and said spacers. 35
13. An improvement in shells comprising a shell body, spacer members located within said body and having radiating arms dividing the interior of the shell into radial shot chambers, and a locking ring within said body provided with longitudinal grooves to be selectively engaged by said arms. 40
14. An improvement in shells comprising a shell body, a plurality of superposed alternately arranged trays and spacers within said body dividing the same into radial shot chambers adapted to effect a tangential discharge of the shot, a locking ring provided with means for preventing rotation of said spacers, and means for preventing relative rotation of the shell body and said locking ring. 45
15. An improvement in shells comprising a shell body, a plurality of superposed alternately arranged trays and spacers within said body dividing the same into radial shot chambers adapted to effect a tangential discharge of the shot, a locking ring having a plurality of longitudinal grooves in its inner face to be selectively engaged by said spacers, and means for preventing relative rotation of the shell body and the locking ring. 50
16. An improvement in shells comprising a shell body, a plurality of superposed alternately arranged trays and spacers within said body dividing the same into radial shot chambers adapted to effect a tangential discharge of the shot, a locking ring having a plurality of longitudinal grooves in its inner face to be selectively engaged by said spacers, means for preventing relative rotation of the shell body and the locking ring, and means for preventing relative rotation of said trays and said spacers. 55
17. An improvement in shells comprising a shell body, a plurality of superposed alternately arranged trays and spacers within said body dividing the same into radial shot chambers adapted to effect a tangential discharge of the shot, said trays having retaining members to engage the shot placed within said chambers, and means for preventing relative rotation of said shell body and said spacers. 60
18. An improvement in shells comprising a shell body, means for dividing the interior of the shell body into radial shot chambers adapted to effect a tangential discharge of the shot, means whereby the tangents on which the shot are discharged may be selectively varied and shot within said chambers, each shot comprising two slugs connected by a chain. 65
19. An improvement in shells comprising a shell body, means for dividing the interior of the shell body into radial shot chambers adapted to effect a tangential discharge of the shot, means whereby the tangents on which the shot are discharged may be selectively varied, and shot within said chambers, each shot comprising two slugs connected by a chain, said slugs being shaped to conform to the contour of the shot chamber in which they are retained. 70
20. An improvement in shells comprising a shell body, means for dividing the interior of the shell body into a plurality of superposed series of radial shot chambers adapted to effect a tangential discharge of the shot, means whereby the tangents on which the shot are discharged may be selectively varied, and shot within said chambers, each 75

shot comprising two slugs connected by a chain, the shot in the respective series of chambers being placed at various distances from the axis of the body.

5 21. An improvement in shells comprising a body having a nose at one end containing an explosive charge, means for dividing the interior of said body into a plurality of radial shot chambers, and means for conveying the explosive gases to the interior of said body at the base thereof.

10 22. An improvement in shells comprising a body having a nose at one end containing an explosive charge, means for dividing the interior of said body into a plurality of radial shot chambers, gas channels leading from said nose to the base of the shell, and means for directing said gases from the base to the interior of the shell.

15 23. An improvement in shells comprising a body having a nose at one end containing an explosive charge, means for dividing the interior of said body into a plurality of radial shot chambers, means for conveying the explosive gases to the interior of said body, and means coöperating with said dividing means to selectively vary the tangents on which the shot may be discharged.

20 24. An improvement in shells comprising a body having a nose at one end containing an explosive charge, a locking ring inclosed within said body, means coöperating with said ring to divide the body into a plurality of radial chambers, and gas channels leading from the nose between the ring and body and discharging into the interior of the shell at the base thereof.

25 25. An improvement in shells comprising a body provided with a base at one end and a nose at the other end, said nose containing an explosive charge, a locking ring having spaced apart lugs resting upon said base, and gas channels leading from the nose, between the ring and the body of the shell, and communicating with the spaces between said lugs.

30 26. An improvement in shells comprising a body provided with a base at one end and a nose at the other end, said nose containing an explosive charge, a locking ring having spaced apart lugs resting upon said base, and gas channels leading from the nose between the ring and the body of the shell, and communicating with the spaces between said lugs, said base being provided with a central table having a grooved surface.

35 27. An improvement in shells comprising a body having a nose at one end containing an explosive charge, a locking ring within said body, superposed spacers and trays dividing said shell body into a plurality of

superposed radial chambers, said spacers engaging said locking ring, and gas channels leading from the nose between the locking ring and the body of the shell and discharging into the interior of the shell at the base thereof.

40 28. An improvement in shells comprising a body having a nose at one end containing an explosive charge, a locking ring within said body provided with longitudinal grooves, superposed spacers and trays located within said body and forming superposed radial chambers, said spacers selectively engaging the grooves of said ring, means for preventing relative rotation of the locking ring and shell body, and gas channels leading from the nose between the locking ring and the body of the shell and discharging into the interior of the shell at the bottom thereof.

45 29. An improvement in shells comprising a body having a nose at one end containing an explosive charge, a locking ring within said body provided with longitudinal grooves, superposed spacers and trays located within said body and forming superposed radial chambers, said spacers selectively engaging the grooves of said ring, means for preventing relative rotation of the locking ring and shell body, gas channels leading from the nose between the locking ring and the body of the shell and discharging into the interior of the shell at the bottom thereof, and means for preventing relative rotation of the spacers and trays.

50 30. An improvement in shells comprising a body having a nose at one end containing an explosive charge, a locking ring within said body provided with longitudinal grooves, superposed spacers and trays located within said body and forming superposed radial chambers, said spacers selectively engaging the grooves of said ring, means for preventing relative rotation of the locking ring and shell body, gas channels leading from the nose between the locking ring and the body of the shell and discharging into the interior of the shell at the bottom thereof, means for preventing relative rotation of the spacers and trays, and means for supporting the trays and spacers in spaced relation to the base of the shell.

55 In testimony whereof I have hereunto set my hand in presence of two subscribing witnesses.
